UNITED STATES PATENT OFFICE.

HYMAN SILVER, OF BROOKLYN, NEW YORK.

DESIGN FOR A REFRIGERATOR.

40,528.

Specification for Design.

Patented Feb. 22, 1910.

Application filed December 16, 1909. Serial No. 533,487. Term of patent 7 years.

To all whom it may concern:

Be it known that I, HYMAN SILVER, a citizen of the United States, residing at Brooklyn, in the county of Kings and State of New York, have invented a new, original, and ornamental Design for a Refrigerator, of which the following is a specification, reference being had to the accompanying drawing, forming a part thereof, and in which is

presented a perspective view of a refrigerator embodying my design.

I claim:

The ornamental design for a refrigerator, as shown.

HYMAN SILVER.
